Inventor:
Howard R. Harrison,
Alexander S. Knott,
His Attorney.

UNITED STATES PATENT OFFICE.

HOWARD R. HARRISON, OF BALTIMORE, MARYLAND, ASSIGNOR TO GENERAL ELECTRIC COMPANY, A CORPORATION OF NEW YORK.

ELECTRIC SWITCH.

Application filed July 5, 1927. Serial No. 203,289.

My invention relates to improvement in electric switches and more particularly to disconnecting switches and has for an object to provide an improved disconnecting switch of the rocking insulator type whereby to obtain a relatively large movement of the blade by a relatively small movement of the rocking insulator and whereby to provide a construction such that, when the switch is mounted vertically, the rocking insulator is not so positioned as to tend to collect and/or retain water.

My invention will be better understood from the following description when considered in connection with the accompanying drawing and its scope will be pointed out in the appended claims.

In the accompanying drawing, Fig. 1 is a side elevation of a single pole disconnecting switch, in the closed position, embodying my invention and Fig. 2 is a side elevation of the switch in the open position.

In the illustrated embodiment of my invention, stationary insulating supports such as two substantially parallel insulators 3, 4 supporting terminals 5, 6 respectively, are suitably secured to a base member shown as a channel 7. Intermediate the insulators 3, 4 is a rocking insulating support such as an insulator 8 mounted in alignment with the insulators 3, 4 for movement about an axis substantially perpendicular to the plane of the insulators 3, 4. For this purpose, the insulator 8 may be secured to a rock shaft 9 in any suitable manner, the shaft being arranged to be actuated by any suitable mechanism shown as comprising a crank 10 and an operating rod 11. While only a single pole switch or switch unit is shown, it is obvious to those skilled in the art that two or more units may have their rocking insulators mounted on the same rock shaft so as to be simultaneously operable.

In accordance with my invention, I provide a contact operating mechanism 12 arranged to be actuated on movement of the rocking insulator 8 so as to obtain an angular contact movement disproportionate to the angular movement of the rocking insulator. As shown, this mechanism is of the pantograph type and interconnects the rocking insulator 8 with the stationary insulator 3. The mechanism comprises a plurality of relatively movable members

such as links 13, 14, 15, 16 which are pivotally connected to form a polygonal linkage. As shown four members or links are employed to form a quadrangular linkage approximating a parallelogram. The link 13 is pivotally connected to the insulator 3 and another link 16 opposite the link 13 is pivotally connected to the rocking insulator 8. The link 16 carries a movable contact such as a blade 17 which is arranged to cooperate with a stationary contact 18, shown as of the jaw type and mounted on the insulator 4. In order to ease the shock due to the chopping action of the blade 17 on engaging its cooperating contact 18 and also to effect a small initial releasing movement of the blades 17 before it is disengaged from the contact 18 on the switch opening movement, the blade is preferably arranged for a limited movement relatively to the link 16. For this purpose the blade 17 may be pivoted at an intermediate point such as 19 to the link 16 and at a point such as 20 adjacent one end through a lost motion slot 21 provided in the link 16. In order to provide a current path independent of the linkage joints, a flexible conductor 22 may be employed to connect the blade 17 with the terminal 5.

In the illustrated embodiment of my invention, the parts are so proportioned that the angular movement of the blade 17 is approximately three times the angular movement of the rocking insulator 8. Consequently even though a short blade be employed the linear velocity of the part arranged to engage the stationary contact 18 can be made relatively high. It will be apparent from Figs. 1 and 2, particularly on considering the left hand edge of the drawing as the bottom, that even though the switch be mounted vertically with the insulator 4 at the top, no concave insulator faces are directed up and therefore there is no tendency for them to collect or retain water.

On further reference to Fig. 1, it will be noticed that as the link 16 is rotated counterclockwise from the position shown, the pivot 20 moves from one end to the other of the slot 21 so that the blade is given an initial combined linear and angular movement which helps to break any sealing action between the blade 17 and the contact 18. On closing the switch, the blade

17 as it touches the contact 18 will yield or move in the opposite direction relatively to the link 16 so that the shocks of entry into the contact 18 is not so great as though 5 the blade 17 and the link 16 formed a rigid member.

What I claim as new and desire to secure by Letters Patent of the United States is:

1. An electric switch comprising two stationary insulating supports, a rocking insulating support mounted intermediate the stationary supports, a pantograph mechanism interconnecting the movable support and one of the stationary supports, a contact mounted on the other stationary support and a cooperating contact carried by said mechanism.

2. An electric switch comprising two stationary insulating supports, a rocking insulating support mounted intermediate the stationary supports, a plurality of movable members pivotally connected to form a polygonal linkage, one of the members being pivoted on the rocking support and another 25 of the members being pivoted on one of the stationary supports and pivotally connected at one point to the rocking support and at another point to the member pivoted thereon, a contact mounted on the other stationary support, and a cooperating contact carried by said one member.

3. An electric switch comprising two stationary insulating supports, a rocking insulating support mounted intermediate the stationary supports, a plurality of movable members pivotally connected to form a polygonal linkage, one of the members being pivoted on the rocking support and another 35 of the members being pivoted on one of the stationary supports and pivotally connected at one point to the rocking support and at

another point to the member pivoted thereon, a contact mounted on the other stationary support, and a cooperating contact carried by said one member and arranged 45 for a limited movement relatively thereto.

4. An electric switch comprising two stationary insulating supports, a rocking insulating support mounted intermediate the stationary supports, a plurality of movable members pivotally connected to form a polygonal linkage, one of the members being pivoted on the rocking support and provided with a lost motion slot and another of the members being pivoted on one of the 55 stationary supports and pivotally connected at two points to the member pivoted on the rocking support and a contact mounted on the other stationary support, and a cooperating contact pivotally connected to said one member through the lost motion slot thereof.

5. An electric switch comprising two stationary substantially coplanar insulating terminal supports, an insulating support 65 mounted intermediate said terminal supports in alignment therewith and for movement about an axis substantially perpendicular to the plane of said terminal supports, four movable members pivotally connected 70 to form a quadrangular linkage, one of the members being pivotally connected to one of the terminal supports and the opposite member being pivotally connected to the movable support, a contact mounted on the 75 other terminal support, and a cooperating contact pivotally connected to said opposite member and arranged for a limited movement relatively thereto.

In witness whereof, I have hereunto set my hand this 30th day of June, 1927.

HOWARD R. HARRISON.
